UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION.

HANDLAMP SWITCH.

Application filed February 21, 1921. Serial No. 446,735.

To all whom it may concern:

Be it known that I, ARTHUR L. STAPLES, a citizen of the United States, residing at New Haven, in the county of New Haven, 5 State of Connecticut, have invented certain new and useful Improvements in Handlamp Switches; and I do hereby declare the following to be a full, clear, and exact description of the invention, such as will enable 10 others skilled in the art to which it appertains to make and use the same.

The present invention relates to portable electric lamps comprising a casing, a battery and an incandescent lamp mounted therein, 15 and a contact device on the casing by which the flow of current from the battery through the lamp may be controlled at will.

In a portable lamp of this character, it is desirable that the user shall be able to flash 20 the lamp, that is, light it for short periods of time, as in signaling, or for such length of time as it is convenient for the operator to hold his thumb on the contact device. It is also desirable that means be provided 25 for closing the switch to light the lamp for a longer period of time and without the need for continuous thumb pressure on the contact mechanism.

It is an object of the present invention to 30 provide a hand lamp with a contact mechanism so arranged that the lamp can be flashed or can be permanently lighted, as desired, but with the additional feature that the contact mechanism cannot be locked in 35 closed-circuit position through accidental pressure on the contact device. This permits the hand lamp to be carried about with tools or in the pocket of an automobile door without the danger that when the lamp 40 is needed its battery will be found exhausted because, through accident, the switch has been closed and the lamp has been lighted without the knowledge of the user.

Other objects and advantages will become 45 apparent from the following description, which is to be taken in conjunction with the accompanying drawings, wherein—

Fig. 1 is a view in elevation of a handlamp constructed in accordance with my invention.

Fig. 2 is an enlarged broken view in central vertical section partly in elevation on the line 2—2 of Fig. 1 showing the circuit closing device in open circuit position.

Fig. 3 is a similar view in closed circuit 55 position.

Fig. 4 is a similar view on the line 4—4 of Fig. 2, with the battery removed to show the inner side of the circuit closing device.

Fig. 5 is a similar view in transverse section on the line 5—5 of Fig. 2.

Fig. 6 is an enlarged broken view in elevation of the circuit closing device of an alternative form of my invention.

Fig. 7 is a similar view in vertical section 65 partly in elevation on the line 7—7 of Fig. 6 showing the circuit closing device in its open circuit position.

Fig. 8 is a view corresponding to Fig. 7, in closed circuit position. 70

Fig. 9 is an enlarged broken view of the inner side of the circuit closing device.

Fig. 10 is a transverse section on the line 10—10 of Fig. 7.

Fig. 11 is a view corresponding to Fig. 6 75 of another alternative form of my invention.

Fig. 12 is a view thereof corresponding to Fig. 7.

Fig. 13 is a view in transverse section on the line 13—13 of Fig. 12. 80

Fig. 14 is a view in transverse section on the line 14—14 of Fig. 12.

In carrying out my invention, as herein shown, I employ a sheet metal escutcheon plate 20 rigidly mounted by means of rivets 85 21 over an opening 22 in the side of an insulating casing 23. An aperture 24 is formed centrally in the escutcheon and is filled flush by a correspondingly shaped push-button 25 struck up from a sheet metal 90 spring contact 26 positioned against the under surface of the escutcheon 20 and rigidly attached at its rear end thereto by a rivet 27. Forward of the button 25, the spring contact 26 is bent inward and forward to lie flat against the inner surface of the casing 23 and extends nearly to the forward end thereof. In the preferred form 95 of my invention shown in Fig. 1 the spring contact 26 is formed with an inward bow 28 which prevents the battery 29, positioned within the casing, from interfering with the contact device and also increases the length of the spring 26 between the rivet 27 and the push-button 25. In the alternative form shown in Figs. 6, through 10, there is no battery positioning means and in the form shown in Figs. 11—14 there is a 100 105

battery positioning spring 30 separate from the spring contact 26, held in place by the rivet 27.

In the preferred form shown in Figs. 1 and 7, the escutcheon lies flat, but in the alternative form shown in Fig. 12 it is raised centrally to simulate the housings employed in hand-lamp contact-devices of the prior art.

10 The escutcheon plate 20 is slotted as shown at 31 in the preferred form in Figs. 4 and 11 at each side of the central opening 24 or as shown at 32 in an alternative form in Fig. 9 forwardly of the opening 24 for the 15 reception of a longitudinally slideable lock 33 mounted therein and having a depending lug 34 integral therewith in Figs. 3 and 12 and attached thereto in Fig. 8. The lug 34 extends through a slot 35 in the spring 20 contact 26. The front face of the lug 34 is vertical and abuts against the front end of the slot 35 whereby it is normally held 25 against forward motion.

In the preferred form, shown in Figs. 3 and 12, the lock 33 is a vertically positioned 25 piece of sheet metal of a more or less rectangular shape having at each end of its upper edge a knurled operating portion 36 while the central part of the upper edge is depressed to lie below the surface of the 30 push-button 26 which the slide traverses. In each end of the lock are longitudinal horizontal slots 37 receiving the metal of the escutcheon 20 at the outer ends of the slots 31 whereby the lock is held slidably in place.

35 In the alternative form, shown in Figs. 8 and 9, the lock has a hollow knurled thumb-piece 38 the side walls of which extend down through the twin slots 32 of the escutcheon 20 and are formed with lugs 39 which are bent inwardly embracing the portion of the escutcheon between the slots 32 and also the narrowed central part of the body 40 of the sheet metal locking lug 34. 40 By this construction the slide comprising the thumb-piece 38 and the lock 34 is held 45 together and in place.

In the forward end of the tube is positioned a reflector 41 of well known form 50 having an insulating strip 42 folded about its outer edge and an electric bulb 43 mounted in its center, the outer terminal of the bulb being in contact with the reflector and the inner terminal in contact with the positive electrode 44 of the battery 29. On the exterior surface of the tube 23 at its forward end is rigidly mounted the customary threaded metal ring 45 upon which is screwed the threaded metal lens mount 46 55 in which the lens 47 is held between the spun in collars 48 and 49. The reflector is held in place by having its outer edge gripped between the end of the tube 23 and the lens supporting collar 48 and is insulated 60 from both by the strip 42.

On the rear end of the tube is the customary construction:—a threaded metal ring 50 rigidly mounted on the tube 23, a sheet metal threaded cap 51 screwed thereon and the spiral metal spring 52 interposed between 70 the naked base of the negative pole of the battery 29 and the cap 51.

A metal conductor strip 53 is hooked over the rear end of the tube 23 under the ring 50 and in electrical contact therewith and extends forward along the inner surface of the tube and is held in place by one of the rivets 21 which also connects it electrically to the escutcheon plate 20. In the preferred form, shown in Fig. 2, the strip 53 terminates just forward of the rivet 21. In the alternative construction, shown in Figs. 7 and 12, the strip 53 extends nearly to the front end of the tube and is further held in place by a rivet 54 which is one of the fastenings of the ring 45. In this construction all of the exposed metal parts of the case are electrically connected to the negative pole of the battery and therefore, since they are all of one polarity, the battery cannot be accidentally short-circuited by external contact of the case with conductive bodies. The preferred form, shown in Fig. 2 is similar in this respect except for the fact that the front ring 45 and the lens support 46 are 95 normally electrically dead.

In the preferred form, shown in Fig. 2, the construction is now completely described. However, under some circumstances it is thought better to give further support against lateral distortion of the contact spring 26. In the alternative form, shown in Figs. 8 and 12, the contact spring 26 is formed near its forward end with a guide slot 55 which receives a vertical guide lug 56 dependent from an integral rivet 57 set in the tube 23 under the ring 45.

When, in use, the push-button 25 is depressed, the spring 26 yields and the outer end thereof contacts with the reflector 41 closing the electrical circuit through the lamp, which lights and remains lit as long as the push-button is depressed. Meantime the spring contact 26 has moved sufficiently to bring the edges of the slot 35 below the lug 34. A forward push on the knurled parts 36 or 38 while the push-button is held down will cause the lug 34 to move forward over the spring 26 in front of the slot 35 and to hold the same depressed until the thumb-piece 36 or 38 is pushed rearwardly again, when the lug 34 will snap into the slot 35 and the front end of the contact spring will again break contact with the reflector.

I am aware that various changes may be made in the details of the present invention without departing from the spirit thereof, as defined by appended claims.

I claim:

1. In a hand lamp, a tubular insulating 130

casing having an opening in the wall thereof, a substantially flat escutcheon covering said opening, a battery and bulb in the casing, and means to close the circuit through the 5 battery and bulb, including a depressible contact strip within the tubular portion of the casing, and having a part disposed in said casing opening below the escutcheon and having its upper surface substantially 10 flush with the upper surface of the casing.

2. In a hand lamp, a tubular insulating casing having an opening in the wall thereof, an escutcheon covering said opening, a battery and bulb in the casing, means to close 15 the circuit through the battery and bulb, including a depressible contact strip within the casing, and having a part disposed in said opening with its upper surface substantially flush with that of the casing, and 20 locking means positioned within the casing opening and movable independently of the contact strip to hold the latter in circuit closing position.

3. In a hand lamp, a tubular insulating 25 casing having an opening in the wall thereof, an escutcheon covering said opening, a battery and bulb in the casing, and means to close the circuit through the battery and bulb, including a depressible contact strip 30 within the casing, said strip being secured to the escutcheon and having a part disposed in said casing opening with its upper surface substantially flush with that of the casing.

4. In a hand lamp, a casing provided with 35 an opening, a battery and bulb mounted in the casing, an escutcheon plate mounted on the casing at said opening, and substantially flush with the surface of the casing, a depressible contact strip carried by the escutcheon and having a part disposed within 40 the casing opening, and means including said contact strip, to complete the circuit through the battery and bulb, and means for locking the switch in circuit closing position.

45 5. In a hand lamp, a casing provided with an opening, a battery and bulb mounted in the casing, an escutcheon plate mounted on the casing at said opening, and substantially flush with the surface of the casing, a 50 depressible contact strip within the casing, having one end secured to said escutcheon, means including said strip to complete the circuit through the battery and bulb, and means movably mounted on the escutcheon 55 for locking the switch in circuit closing position.

6. In a hand lamp, a tubular casing having an opening in the wall thereof and an escutcheon plate covering the opening, a 60 battery, a bulb support and a light bulb in the casing, and means to close the circuit through the battery and bulb, including a depressible contact member secured at one end to the escutcheon within said opening, 65 extending along the inner surface of the

casing and adapted to contact at its other end with the bulb support.

7. In a hand lamp, a casing having an opening therein and an escutcheon plate covering said opening, a battery, a reflector and a light bulb mounted within the casing, and means for completing the circuit through said bulb and battery comprising a contact strip adapted to engage the reflector and secured at one end to the escutcheon 70 and a push button normally flush with the surface of the casing to depress said strip and close the circuit. 75

8. In a hand lamp, a tubular casing having an opening in the wall thereof, and a flat escutcheon plate mounted over said opening, a depressible contact strip secured at one end to the escutcheon within said opening and formed with an integral upward projection adapted for manual engagement 80 through an opening in the escutcheon and lying substantially flush with the upper surface of the escutcheon, said contact strip also being formed with a forwardly extending portion adapted to lie closely against 85 the inner surface of the casing. 90

9. In a hand lamp, an insulating casing having an opening and an escutcheon plate covering said opening, a battery and a reflector mounted within the casing, a lamp bulb having one terminal in connection with the battery and the other terminal electrically connected to the reflector, a contact strip secured at one end to the escutcheon plate and having its other end free and positioned to be depressed into contact with the reflector, means for connecting the other terminal of the battery to the contact strip, and means movable to position between the contact strip and the escutcheon to lock the 95 strip in circuit closing position. 100

10. In a hand lamp, a casing having an opening therein, an escutcheon plate covering said opening, a battery, a reflector and a light bulb mounted within the casing, and means for electrically connecting the battery and bulb, including a contact strip secured at one end and having its other end in position to be depressed into engagement with the reflector, said contact strip being 110 formed with a push button in position to be manually engaged and a locking member mounted on the escutcheon and slidably to a position between it and the contact strip 115 to lock the latter in circuit closing position. 120

11. In a hand lamp, an insulating casing provided with an opening, an escutcheon plate covering said opening, a battery and bulb support housed in the casing, a bulb mounted in said support and means to close the circuit through the battery and bulb, including a depressible contact strip lying closely adjacent the inner surface of the casing and formed with an upwardly projecting portion extending into the casing 125 130

- opening, and being there connected to the escutcheon.
12. In a hand lamp, a casing, a battery and light bulb mounted therein, and means 5 for closing the circuit through said battery and bulb, including a depressible contact strip formed with a bowed battery positioning portion, said portion serving as a fulcrum for said strip:
- 10 13. In a hand lamp, an insulating casing provided with an opening, an escutcheon plate covering said opening, a battery and bulb support housed in the casing, a bulb mounted in said support and means to close 15 the circuit through the battery and bulb, including a depressible contact strip lying closely adjacent the inner surface of the casing and formed with an upwardly projecting portion extending into the casing 20 opening, said part being manually engagable through an opening in the escutcheon to depress the contact strip to close the circuit.
14. In a battery hand-lamp, an insulating 25 casing: a battery therein; a reflector mounted in one end of said casing: an electric bulb mounted therein, having one of its terminals electrically connected to one of the electrodes of the said battery and the other 30 terminal electrically connected to the said reflector: a conductive member mounted in the said casing and electrically connected with the other electrode of the said battery: and a circuit closing device mounted on the 35 said casing, electrically connected to the said conductive member; said circuit closing device having a push-button and a spring contact member, adapted to contact with the said reflector when pressure is applied to the said push-button, thereby closing the circuit of the said battery through the said bulb; and having means locked 40 against movement while the said spring contact is in its open circuit position and movable when the said spring contact is in its closed circuit position to hold the same in such position.
15. In a battery hand-lamp, an insulating 45 casing: a battery therein: a reflector mounted in one end of said casing: an electric bulb mounted therein, having one of its terminals electrically connected to one of the electrodes of the said battery and the other terminal electrically connected to the said reflector; a conductive member mounted in the said casing and electrically connected with the other electrode of the said battery: and a circuit closing device mounted on the said casing; electrically connected to the said conductive 55 member; having a push-button and a spring contact member, adapted to contact with the said reflector when pressure is applied to the said push-button, thereby closing the circuit of the said battery through the said bulb; and having means locked against movement 60 while the said spring contact is in its open circuit position and movable when the said spring contact is in its closed circuit position to hold the same in such position.
16. In a battery hand-lamp, an insulating 65 tubular casing having a metal collar mounted on the bottom end thereof: a battery positioned in the said casing: a metal cap removably mounted on said collar, in electrical contact therewith, and closing the end of said casing: a metal spring interposed between the lower electrode of said battery and said cap and electrically connecting the same: a metal reflector mounted in the top end of said casing: an electric bulb mounted in said reflector, having its terminals electrically connected to said reflector and the upper electrode of said battery respectively: a conductive strip electrically connected to said metal collar, mounted in said casing: an aperture in said casing: an escutcheon having an opening therein mounted over said aperture and electrically connected to said conductive strip: a spring contact member, mounted within said casing, rigidly held at its lower end, electrically connected to said escutcheon, having a push-button rising through said opening and having its free upper end in proximity to but not in contact with said reflector when said member is in its normal open circuit position, and adapted to be moved against its own tension when pressure is applied to said push-button into contact with said reflector whereby the circuit of said battery through said bulb is closed: and means mounted on said escutcheon and movable, after said contact member has been moved to its circuit closing position, to hold the same in such position.
17. In a battery hand-lamp, an insulating 70 casing; a battery therein; an electric bulb mounted in a metal support in one end of said casing, one of the terminals of the said bulb being electrically connected with the said support and the other terminal of the bulb being electrically connected with one of the electrodes of the said battery: a conductive member mounted in the said casing and electrically connected with the other electrode of the said battery: and a circuit closing device mounted on the said casing; electrically connected to the said conductive member; having a push-button, and a spring contact member adapted to contact with the said support when pressure is applied to the said push-button, thereby closing the circuit 75

of the said battery through the said bulb; and having means movably mounted within the casing and adapted to be moved into contact with the upper surface of said spring 5 contact member to hold the latter in circuit closing position.

18. In a hand lamp, an insulating casing having an opening in the lateral surface thereof, and a flat escutcheon plate covering 10 said opening, a battery and reflector and a light bulb within the casing, and means for completing a circuit through said bulb and battery comprising a contact strip to engage the reflector and secured at one end to 15 the escutcheon within said opening, and a push button normally flush with the surface of the escutcheon to depress said strip to close the circuit.

19. In a hand lamp, an insulating casing 20 having an opening in the wall thereof, an escutcheon covering said opening, a battery and a bulb mounted within the casing, and means for electrically connecting the battery and bulb, including a contact strip within 25 the casing, and secured at one end to the escutcheon and depressible at its other end

to close the circuit, said contact strip being formed with a push button to be manually engaged, and a locking member slidable to position between said contact strip and 30 escutcheon to lock the strip in circuit closing position.

20. In a hand lamp, an insulating casing having an opening in the wall thereof, an escutcheon plate covering said opening, a 35 battery and bulb within the casing, and means to close the circuit through the battery and bulb including a switch device having a depressible contact member within the casing, a push button manually engageable 40 through an opening in the escutcheon and having a slot in its upper face and a locking member carried by said escutcheon and disposed within said slot.

In testimony whereof, I have signed this 45 specification in the presence of two subscribing witnesses.

ARTHUR L. STAPLES.
